UNITED STATES PATENT OFFICE.

RALPH W. ERSKINE, OF MISHAWAKA, INDIANA, ASSIGNOR TO WESTINGHOUSE, ELECTRIC & MANUFACTURING COMPANY, A CORPORATION OF PENNSYLVANIA.

SUPPORTING STANDARD.

Application filed January 16, 1928. Serial No. 247,233.

My invention relates to trolley poles and it has particular relation to ornamental trolley-wire supports which may be utilized as standards for supporting lighting units and 5 the like.

In some thickly populated districts, trolley wires are usually suspended by standards or poles placed along the curb, and, since these districts must be well lighted, still 10 another set of standards is utilized for supporting the lighting units. This condition leads to a multiplicity of standards placed along the curb which are unsightly and which interfere with pedestrian traffic.

15 My invention is directed to an ornamental trolley pole which may be also utilized for supporting lighting units, thereby reducing the number of standards in any given district.

20 Therefore, an object of my invention is to provide a combination lighting standard and trolley pole which will be ornamental and in which the trolley-wire-supporting means are concealed.

25 Another object of my invention is to provide a device of the above description, which is simple and rugged in construction and which may be manufactured at a low cost.

Still other objects of my invention will be 30 come apparent from the following description of my device.

Referring to the drawing, in which like figures indicate like parts,

Figure 1 is a view, partly in section and 35 partly in elevation, of a combination trolley pole and lighting standard constructed according to my invention;

Fig. 2 is a view, in cross section, taken along the line II—II of Fig. 1.

40 Referring to the drawing, I prefer to utilize, as the trolley-wire-supporting means, a hollow steel standard or pole 1 of any suitable type. A four-piece ornamental lighting standard 2 is placed over the supporting standard to enclose it, either before or after erection. The supporting standard may have 45 its lower portion 3 buried in the ground, while the ornamental standard, which is braced by the supporting standard and is not subjected to lateral strain, may rest upon the 50 surface of the ground.

The supporting standard is provided, at its upper end, with a two-part collar 4, which is fastened in place at the top of the standard 55 by means of bolts 5. The collar is pro-

vided with threaded openings 6 into which hook-shaped bolt members 7 may be inserted for supporting the trolley wire at points other than at the point nearest the standard. Other supporting members, such as a rod 8, 60 which is utilized for supporting overhead wiring extending parallel to the supporting arms of the standard, are provided to engage the bolts 5 which fasten the split collar to the supporting standard. 65

The ornamental standard may comprise four sections, including a base section 11, a column section 12, a supporting head 13 and a cap or finial 14. Lighting units 15 may be fastened on the head at its upper portion 16 70 by means of a fitter 17, or in any other well-known manner. The conductors for furnishing electrical energy to the lamp of the lighting unit may be brought into the standard through openings 18. 75

The ornamental work of the head 13 is so designed that small circular figures 19 are provided at the central portion of the head. The material at the outer portion of these figures is made of decreased thickness, so 80 that the circular figures may easily be removed by a blow from a hammer. Other so-called "knock-out" portions 20 are provided at the outer extremities of the supporting arms so that the rods 8 may be inserted 85 therethrough.

In erecting the standard, as, for instance, for supporting trolley wires, the supporting standard is sunk in the ground and the base 90 11, column 12 and head 13 of the ornamental standard placed over the supporting standard. The collar 4 is then bolted in place. Such "knock-outs" are removed as will be necessary to furnish the desired support for the trolley wire, and the supporting hook 95 members 7 are inserted through the openings thus provided and threaded into the collar 3. If one of the trolley-wire supports is desired at the end of the supporting arms of the head 13, the corresponding "knock-out" 100 is removed, and the rod 8 inserted through the opening thus provided and fastened to a bolt 5 of the collar 4. The trolley-wire-supporting wires or cables are then fastened to the hook members 7. 105

My trolley-wire-supporting means are inconspicuous, especially at night, when the shadow cast by the fitter 17 prevents the outer portion of the supporting rods from being clearly seen. The structure is ornamental 110

and provides a very effective lighting standard, since the lighting units are placed at a considerable distance above the ground.

Although I have described only one specific embodiment of my invention, modifications may be made by those skilled in the art without departing from the spirit and scope of the invention, as defined in the appended claims.

10 I claim as my invention:

1. A support for overhead wiring comprising a supporting standard, an ornamental standard surrounding said supporting standard, and fastening means for supporting the overhead wiring comprising a collar on the supporting standard, bolts engaging said collar, portions of the ornamental standard being made of relatively thin material in

order to permit removal of the portions for insertion of parts of said supporting means. 20

2. A lighting standard comprising a supporting standard, an ornamental standard covering said supporting standard and having an ornamental lamp-supporting head, means comprising "knock-outs" in the column and lamp-supporting arm of the ornamental head for permitting attachment to the supporting standard of overhead wiresupporting means, the outline of the "knock-outs" constituting a portion of the design 30 figures on the ornamental head.

In testimony whereof, I have hereunto subscribed my name this 7 day of January, 1928.

RALPH W. ERSKINE.
